CARTON

Clyde J. Norris, West Chicago, and Victor Porth,
Chicago, Ill., assignors to The Chicago Label
& Box Co., Chicago, Ill., a corporation of Illinois

Application December 30, 1933, Serial No. 704,672

6 Claims. (Cl. 229—17)

This invention relates to improvements in cartons, and has among its objects to provide a sealed container of such character that after the seal is broken a spout is available for pouring contents, such spout being collapsible to form a closure when not in use; to provide a box of the character described which may be economically manufactured and sold in knocked-down form, and to provide a box in which the spout member is an integral part of the box itself.

These and other objects are more fully set forth and described in the following specification and shown in the accompanying drawing, in which:

Fig. 1 is a plan view of the cut and scored blank;

Fig. 2 is a view of the completed and sealed carton drawn to a larger scale;

Fig. 3 is a section along the line 3—3 of Fig. 2 on a still larger scale;

20 Fig. 4 is a perspective of a part of the box showing the spout portion in opened position;

Fig. 5 is a view similar to Fig. 4 showing the side wings folded inwardly; and

25 Fig. 6 is a plan view of the top of the box showing the spout portion closed after the wings have been moved to the position illustrated in Fig. 5, this figure being drawn to smaller scale.

Like numerals refer to like elements throughout the drawing, in which

30 10 indicates generally a blank cut out of suitable material, such as paper boxboard, or the like, the blank being formed with the side portions 11, 12 and the end portions 13, 14. Reinforcing tongue 15 projects from the side 11, as illustrated in Fig. 1. To form the ultimate bottom of the carton, we have provided the bottom flaps 11—a, 13—a, 12—a and 14—a, respectively, each severed from the contiguous flaps by a cut, as illustrated. To form the ultimate top are the flaps 11—b, 13—b, 12—b and 14—b, while the reinforcing tongue 15 is provided with a bottom tab 15—a and a top tab 15—b, these latter tabs being cut adjacent the flaps 11—a, 11—b, as illustrated. Slight notches 12—x are provided at the juncture of the tab 12—c and the flap 12—b to enhance the locking effect of the tab after the package has been once opened. Flap 11—b is also cut along the edge 11—c.

50 The bottom flaps 11—a to 15—a, inclusive, are scored along the line A to provide hinge points. Similarly a scoring or bending line B is provided at the juncture of the upper flaps 11—b to 15—b, inclusive.

Projecting outwardly from the flaps 13—b and

14—b are the tabs 13—c, 14—c, while from the flap 12—b projects a small tab 12—c.

The portion of the top flaps between tabs 12—c and 13—c are scored along the diagonals C, D and are provided with the bisecting scoring line E. Similarly, between the upper flaps 12—b and 14—b are provided the scoring lines F, G and H.

In assembly of the box, the blank may be bent along the scoring line between body portions 12 and 13 and the tongue 15 bent to underlie end 10 portion 14 to which it is suitably secured, as by gluing or the like. This partially completed carton may be shipped in this flat marked-down form, if so desired.

In the completion of the carton, it is desirable 15 first to effect the closure and sealing of the top before charging the carton with whatever material is to be packaged therein. One method of folding and sealing the top portion which we have found satisfactory, is as follows: The blank, partially assembled as described above, is forced to expanded position, after which all of the flaps except 11—b are folded to assembled relation with the tab 12—c located as illustrated in Fig. 3. The tabs 13—c and 14—c are suitably secured 20 in folded position as by gluing, or the like, after which the flap 11—b is folded down and glued, or otherwise suitably secured to the underlying portion of the box. To effect these operations, any suitable mechanism or apparatus may be 25 utilized, although it is preferable to utilize an anvil block in the interior of the carton with a presser member to press the members into folded and secured relation, this in cooperation with the anvil block. The tab 12—c will assume the 35 position as indicated in Fig. 3 of the drawing.

The carton may then be charged with the material to be packaged and the bottom flaps 11—a, 12—a and 14—a folded to final position and secured therein as by gluing, or the like.

40 A label or sealing member 20 is placed upon and glued to the folder top, as illustrated in Fig. 3, at any suitable time during the completion and closing of the carton.

When it is desired to pour out the contents of 45 the carton, the label 20 may be cut or severed along the free edge of flap 11—b and at its ends, following which the user may insert a finger beneath the flap 11—b to hook or engage the tab 12—c and lift the hinged flap 12—b to the position illustrated in Fig. 4, in which condition a narrowing spout is provided which permits accurate and easy pouring of the contents of the carton into any desired receptacle. If the entire content of the carton is not removed at one time, 50 55

the remainder may be substantially sealed against the entrance of moisture or the escape of valuable constituents thereof by reinserting the tab 12-c into the interior of the box, as illustrated in Fig. 3, in which position there is sufficient resistance afforded by such tab to hold the hinged flap of the top in closed position. The notches 12-x contribute to the maintenance of the cover in closed position. If preferred, the bellows-like 10 wings may be folded in, as illustrated in Fig. 5, before closure of the hinged flap, in which event the top will appear as illustrated in Fig. 6.

It will be apparent that these bellows-like 15 wings and the converging edges D and F of the hinged flap provide what I have termed above a narrowing spout, which serves to concentrate any substance poured from the carton into a relatively small stream, thereby reducing or eliminating the possibility of spilling the contents when 20 directing them into a cup, glass, or other receptacle.

It will be apparent that our invention is susceptible to modification, and we do not wish to be restricted to the embodiment illustrated and 25 described, except as the appended claims limit us thereto properly interpreted with respect to the prior art.

What we claim is:

1. A carton comprising a body portion, a top, 30 said top including a hinged flap, a complementary flap secured in closed position, collapsible wings attached to said hinged flap, the edges of said collapsible wings and the inward edge of said complementary flap substantially meeting in a straight line to facilitate slitting the sealing 35 means, said hinged flap and said collapsible wings comprising a spout for said carton when in opened position.

2. A carton comprising a body portion and a top, 40 said top comprising two side flaps and two end flaps, one of said side flaps being secured to said end flaps in closed position, the other side flap being hinged, collapsible wings extending between said end flaps and said hinged flap, said 45 hinged flap having a projecting tab, said tab being constructed to underlie said other side flap in closed position and coacting with said end flaps to provide positive closing means for said carton.

3. A carton comprising a body portion and a top, 50 said top comprising two side flaps and two end flaps, one of said side flaps being secured to said end flaps in closed position, the other side flap being hinged, collapsible wings extending be-

tween said end flaps and said hinged flap, means on said hinged flap releasably to secure said hinged flap in closed position, said last named means including a tab, said tab having side notches at its junction with said hinged flap, 5 said notches engaging said end flaps when said hinged flap is in closed position.

4. An article of manufacture comprising a blank for a carton, said blank being provided with side wall portions and top portions hingedly 10 secured thereto, one of said top portions being free at its ends, another top portion being provided with bending lines converging from its hinged connection to said side wall portions and having locking means projecting from its edge 15 remote from its hinged side, the adjacent top portions being provided with oppositely directed bending lines to form with said first named bending lines collapsible bellows-like wings and having projections adapted to cooperate with said 20 locking means.

5. In a carton, end flaps and side flaps, one of said side flaps being secured in closed position, the other having a tab on the inner edge thereof and being releasable at will, collapsible wings attached to the sides of said last named flap, said end flaps being adapted to underlie the secured side flap, each said end flap having one of said collapsible wings attached to provide walls of a pouring spout when said releasable side flap is 30 opened, notches at the junction of said tab with said releasable side flap, said tab being adapted to underlie said closed side flap and said end flaps when said releasable side flap is in closed position, said notches being adapted to engage with the 35 said end flaps as they lie beneath said closed side flap.

6. In a container having a pouring spout, a pouring flap having collapsible wings on the sides thereof, a closed flap complementary to said 40 pouring flap, and end flaps adapted to underlie said closed flap, said end flaps being so shaped that they partially underlie said pouring flap, whereby an orifice is created upon the opening 45 of said pouring flap through which the matter in the container may be poured, a tab member on said pouring spout, notches in said tab member at its junction with the pouring flap, said notches interlocking with said end flaps when the pouring 50 flap is in closed position.
